UNITED STATES PATENT OFFICE.

WILLIAM N. BOOTH, OF DETROIT, MICHIGAN.

NUT.

Application filed July 31, 1922. Serial No. 578,728.

The invention relates to the manufacture of acorn nuts and has for its object the production of acorn nuts at decreased cost in which a plug blank is secured to an end of the interiorly threaded apertured body blank and the external surfaces of the body and plug blanks are subsequently finished. With this and other objects in view, the invention resides in the novel features as more fully 10 hereinafter set forth.

In the drawings:

Figure 1 is a section through the body blank;

Figure 2 is a section through the assembled body and plug blanks;

Figure 3 is a section through the plug blank;

Figure 4 is a sectional elevation of the finished acorn nut;

Figure 5 is a plan view thereof.

1 is the body blank having the polygonal portion 2 and the annular flange 3 at its inner end. 4 is an aperture extending axially through the body blank and terminating at the outer end thereof in the enlarged portion 5, the portion of the aperture between the enlarged portion and the inner end of the body blank being threaded. 6 is an annular plug blank of a diameter to have a press fit in the enlarged portion 5 of the aperture at the outer end of the body blank. If desired, this plug blank may be more positively secured to the body blank as by spot welding.

After the plug blank has been secured in the outer end of the body blank as shown in Figure 2, the external surfaces of the body and plug blanks are then finished which includes the rounding of the outer end of the body blank and also the rounding of the outer face of the plug blank as shown in Figure 4.

With this method, the cost of production of the acorn nut is decreased since the machining operations may more readily be carried out.

What I claim as my invention is:

1. An acorn nut comprising a body having an axial aperture therethrough with an enlarged portion in the outer end thereof, the portion of the wall of said aperture between the enlarged portion and the inner end of said body being threaded, and a plug having a press fit in the enlarged portion, the outer end of said plug being rounded and the outer surface of said body being rounded in continuation of said outer end.

2. In an acorn nut having an internally threaded inner end portion and a relatively thick flat plug having a press fit into the outer end of said body, the outer ends of said plug and body being rounded in continuation of each other.

In testimony whereof I affix my signature.

WILLIAM N. BOOTH.
